UNITED STATES PATENT OFFICE.

EDWARD ERMOLD, OF NEW YORK, N. Y.

BOTTLE-LABELING MACHINE.

SPECIFICATION forming part of Letters Patent No. 636,967, dated November 14, 1899.

Application filed June 19, 1899. Serial No. 721,166. (No model.)

To all whom it may concern:

Be it known that I, EDWARD ERMOLD, a citizen of the United States, residing in the city of New York, in the borough of Manhattan and State of New York, have invented certain new and useful Improvements in Bottle-Labeling Machines, of which the following is a specification.

This invention relates to certain improvements in the picker mechanisms of bottle-labeling machines, and more especially to the picker mechanism shown and described in United States Letters Patent No. 632,519, granted to me September 5, 1899, so that in place of the stationary pickers a positive lateral motion is imparted to the pickers, whereby the more reliable and effective action of the same is obtained, especially when pasting on labels of smaller size than the diameter of the bottles.

The picker mechanism shown in the specification referred to is composed of laterally-yielding spring-cushioned guard-plates and stationary pickers below the same. This required a special set of pickers for each size of bottle to be labeled, which was found to be inconvenient in use, as the same set of pickers could not be used for different sizes of bottles and labels.

The object of this invention is to so improve the picker mechanism for bottle-labeling machines that the same set of pickers can be used for any size of bottle or label in connection with the laterally-yielding guard-plates; and for this purpose the invention consists of a picker mechanism for bottle-labeling machines which comprises laterally-movable and spring-actuated guard-plates, laterally-shiftable pickers located below the same, the shanks of said pickers being guided in ways of the picker-frame, and means for returning the pickers into their normal position with each backward stroke of the picker-frame, so as to be ready for the next picking action of the same.

The invention consists, further, of a picker mechanism for bottle-labeling machines which comprises laterally-movable and spring-actuated guard-plates, laterally-shiftable pickers below the same, ways arranged in the picker-frame for guiding the shanks of said pickers, antifriction-rollers at the rear

ends of said shanks, and stationary cam-rails at opposite sides of the main frame of the labeling-machine for returning the pickers from their laterally-shifted position into normal position, as will be fully described hereinafter and finally pointed out in the claims.

In the accompanying drawings, Figure 1 represents a front elevation of a portion of a labeling-machine with my improved picker mechanism, showing the guard-plates, laterally-shiftable pickers, spring-actuated wipers, and the plunger for forcing the bottle through between the guard-plates, pickers, and wipers. Fig. 2 is a similar front elevation of my improved picker mechanism, showing the parts in position for applying the label to the bottle. Fig. 3 is a vertical transverse section through the picker mechanism on line 3 3, Fig. 2. Fig. 4 is a detail plan view of the picker mechanism; and Fig. 5 is a horizontal section of the same on line 5 5, Fig. 1.

Similar letters of reference indicate corresponding parts.

Referring to the drawings, A represents the supporting-frame of my improved bottle-labeling machine.

a a are stationary guide-rods, on which the reciprocating picker-carriage B is guided by suitable sleeves a'.

D is a vertically-reciprocating plunger by which the bottle is moved in downward direction, so as to take up the label with its pasted edges.

At the sides of the picker-carriage B are arranged the laterally-movable and spring-actuated guard-plates C, and below the same the pickers P, which are likewise guided in lateral ways of the picker-carriage B. Below the pickers P are arranged the laterally-oscillating and spring-actuated wipers F, by which the label after being pasted at its opposite rear edges, is applied to the bottle when the same is forced through between the guard-plates and pickers. The parts referred to are located approximately in a vertical plane, one below the other, when the label is applied to the bottle, as is more fully described in the specification of Letters Patent 100 before referred to.

The picker-carriage B is reciprocated on the guide-rods a a by means of a suitable mechanism actuated by a driving cam-shaft. (Not

shown.) The pickers P are arranged parallel with each other at the front part of the picker-carriage in such a manner that during the forward motion of the picker-carriage 5 their faces come in contact with paste-supplying rollers, so as to take up the paste, and are then lowered, so as to pick up the uppermost label from a label-elevator. As soon as the label is taken up by the pickers the picker-carriage is raised again, and the pickers continue their forward motion until they arrive vertically in line with the plunger D and a stationary bottle-rest G, that is located below the wipers. The actuating mechanism of the vertically-reciprocating plunger, laterally-shiftable pickers, and oscillating wipers is so timed that as soon as the label is removed from the pickers by the downward motion of the plunger and transferred to the 10 bottle by the wipers the picker-carriage begins its backward stroke, while during the forward stroke the pickers take up a new supply of paste and a new label to be applied to the next bottle to be labeled.

25 The guard-plates C are curved in downward direction, so that the bottle passes readily between the same, their shanks being guided in brackets B' of the picker-carriage and cushioned by means of helical springs d, interposed between the guard-plates and stationary sockets d' on the picker-carriage, as shown in Fig. 4. The pickers P are guided by shanks e in transverse ways at the lower part of the brackets B' of the picker-carriage, the outer ends of said shanks being provided with antifriction-rollers r, which are placed in contact with stationary cam-rails f, that are arranged horizontally at each side of the supporting-frame A of the bottle-labeling machine. The cam-rails f are supported in position by means of clamping-screws f' on slotted brackets f² of the supporting-frame A, said rails being made narrow at their front ends and the latter connected by inclines 40 with the wider rear ends, as shown in Fig. 5. The pickers P are provided with horizontal faces at their under sides that take up the paste from the paste-rollers for transference to the opposite rear edges of the label. The 45 distance of the pickers from each other corresponds to the size of the label; but when the bottle is passed by the descending plunger through between the guard-plates, pickers, and wipers the pickers are moved laterally 50 in their guideways by the bottle to a distance corresponding to the diameter of the bottle. The cam-rails f can be adjusted laterally on their supporting-brackets by means of slots being provided in the brackets for this purpose. The guard-plates C are so adjusted 55 as to be closer together than the pickers P, their distance from each other being smaller than the diameter of the bottle, while the distance between the pickers corresponds to the 60 size of the label, so that their gummed faces can freely take up the label and transfer the same to the bottle. When the plunger forces

the bottle in downward direction, it presses the guard-plates and pickers sidewise, so that the wipers can act on the ends of the label 70 and apply the same to the bottle, as shown in Fig. 2. The distance of the guard-plates C from each other is adjusted according to the size of the bottle, while the position of the pickers is adjusted by the cam-rails according to the sizes of the label, the cam-rails being so adjusted that they return the pickers during the backward stroke of the picker-carriage into their normal position toward each other ready to take up the next supply of 80 paste and then pick up the next label. The shanks of the pickers slide freely in the transverse ways of the brackets B' of the picker-carriage, they being shifted sidewise by the bottle under the action of the descending 85 plunger and returned again to their former position by the action of the cam-rails, no yielding or spring-actuated motion being required, as they are returned into normal position 90 ready for the next labeling operation by the positive action of the stationary cam-rails on their shanks.

The operation of my improved picker mechanism can be readily understood from the foregoing description. When the picker-carriage 95 arrives at the end of its forward stroke, the bottle is placed in position below the plunger, the descending motion of which forces the bottle through between the guard-plates and pickers, so as to take up the pasted ends of the labels, which by the continued descending motion of the bottle are pressed on the same by the action of the elastic wiper. The spring-actuated guard-plates yield sufficiently during the downward motion of the bottle, likewise the 100 pickers, so that the label is removed from the face of the pickers and transferred to the bottle by the wipers, said wipers imitating the action of the fingers of the hand in applying the label to the bottle. After the bottle has passed the wipers it is taken up by the stationary 105 bottle-rest G below the same, the neck of the bottle being held during the downward motion by the attendant. The bottle is then removed and the next bottle placed below the 110 plunger and carried downward again by the descending motion of the same when the picker-carriage arrives again at the end of its 115 next forward stroke. During the ascending motion of the plunger the picker-carriage is moved in backward direction, during which motion the antifriction-rollers on the outer ends of the picker-shanks are moved along the cam-rails, so that the pickers are shifted 120 and returned to their normal position in which to take up the next label and carry it forward for transference to the bottle. The laterally-shiftable pickers have the advantage that any size of labels, whether large or small, can be applied with equal facility to the bottle by the 125 simple adjustment of the cam-rails away from or toward each other on their supporting-brackets, provided the pickers are at such a 130 distance from each other that they take up

the labels in a reliable and effective manner and transfer them by the joint action of the descending plunger on the bottle and of the wipers on the label to the bottle to be labeled.

5 Having thus described my invention, I claim as new and desire to secure by Letters Patent—

1. In a bottle-labeling machine, the combination of a reciprocating picker-carriage, laterally-yielding and spring-actuated guard-plates supported by said carriage, laterally-shiftable pickers below said guard-plates, and means whereby the backward motion of the picker-carriage causes said pickers to return 15 to their normal positions, substantially as set forth.

2. In a bottle-labeling machine, the combination of a reciprocating picker-carriage, laterally-yielding and spring-actuated guard-plates supported by said carriage, laterally-shiftable pickers below said guard-plates, means for laterally guiding said pickers in brackets of the carriage, and parallel cam-rails engaging the picker-shanks and return- 20

ing the pickers into their normal position during the backward stroke of the picker-carriage, substantially as set forth. 25

3. In a bottle-labeling machine, the combination of a reciprocating picker-carriage, laterally-yielding and spring-actuated guard-plates supported at the front portion of the carriage, laterally-shiftable pickers below said guard-plates, means for guiding the shanks of said pickers in brackets of the picker-carriage, parallel cam-rails at each side 30 of the supporting-frame, and means for adjusting said cam-rails, said cam-rails serving to return the laterally-shiftable pickers into their normal position during the backward stroke of the picker-carriage, substantially as 35 set forth. 40

In testimony that I claim the foregoing as my invention I have signed my name in presence of two subscribing witnesses.

EDWARD ERMOLD.
